UNITED STATES PATENT OFFICE.

HENRY DRYSDALE, OF WANDSWORTH, LONDON, ENGLAND.

SINGLE-ROLL WET MILL.

Application filed June 11, 1926, Serial No. 115,180, and in Great Britain March 19, 1926.

This invention relates to improvements in single roll wet mills and the like for grinding paint, wet mixed pigments, inks and other allied materials and relates to that type in which the roller has axial reciprocation and in which a grinding bar or block circumferentially contacting with said roller is adjustably mounted in relation thereto.

Heretofore in machines of this type it has been necessary to keep a mill for each colour or shade of colour, or, alternatively, to remove a large portion of the hopper and roller housings to clean down, the reassembly necessitating skilled labour since the roller must be aligned and the housing and hopper adjusted to prevent loss of materials passing out endwise or escaping through the block due to faulty setting. Further, owing to wear on the grinding blocks being accentuated over its surface intermediate the ends, adjustment on resetting must be exact to former position otherwise the operative surface of the block ceases to contact with the roller, or contacts at one side only, and the machine in such condition is useless for its purpose.

Now according to the present invention the mill not only retains its feature of reciprocating roller and adjustable grinding block but the hopper and feed throat are made removably hinged whereby the roller and housing surfaces can be sponged clean and the grinding block surface so adjusted that skilled setting is unnecessary and the attendant single-handed can clean, refix and adjust for fresh material.

Reference will now be made to the accompanying drawings which illustrate by way of example a grinding mill constructed according to the invention and in which:—

Figure 1 is a side elevation,
Figure 2 is an end elevation,
Figure 3 is a cross sectional elevation and
Figure 4 is a detail view showing the operative surface of the grinding block.

In the form illustrated a hopper 1 is secured to a throat 2 through which the material to be ground is fed onto the surface of a roller 3. The throat 2 and hopper 1 are carried in a frame 4 carried at one side of the machine on a hinge spindle 5 at one end of which is mounted a worm wheel 6 meshing with a worm 7 on a spindle 8 carrying a wheel 9 for manual operation. The frame 4 is normally secured in the operative position shown in the drawings by means of eye bolts 10, the lower

ends of which enter sockets in the main framework 11 of the mill where they are engaged by bolts 12 around which they can move pivotally when nuts 13 are slackened to allow the frame 4 to be swung about the spindle 5 thereby affording access to the interior surfaces of the throat and the working face of the roller for cleansing purposes. The under surfaces of the frame 4 and the surfaces of the framework 11 upon which they rest may be tongued and grooved to obviate end play and take up any thrust resultant from the axial movement of the roller. In order to counterbalance the frame 4 when in its raised position it is preferred to provide a weight 50 suspended from an arm 51 keyed to the hinge spindle 5.

To render the throat 2 and hopper 1 capable of adjustment towards or from the surface of the roller independently of the hinge movement they are mounted in the frame members 4 by means of lateral extensions 14 on the throat each of which engages over a pair of micrometer screws 15 engaging the frame members 4. These screws are locked in their adjusted positions by means of grub screws 16. The hopper and throat are then held in position at the desired height by screwing down nuts 17 whilst the throat takes its main bearing through a central pin 18.

Formed integral with the throat 2 and hopper 1 is a housing 19 for a grinding block or bar 20 which is secured in position in the housing by means of wing nuts 21. Extending across the machine above the said grinding block housing is a cross bar 22 secured to the frame members 11 by wing nuts 23. Through the cross bar pass bolts 24 and 25, the former carrying wing nuts 26 bearing upon springs 27 by varying the compression of which the pressure on the grinding block can be varied. The bolts 25 have milled heads 28 formed thereon and also bear upon the grinding block constituting means for adjusting the position of the latter. The working face of the grinding block is shown in Figure 4, the lines A and B indicating the mid position of the reciprocating roller 3. The ends 29 of the grinding block are of enlarged area but have their central portions removed so that at those points where only half the wear is experienced compared with the central portion of the bar, the surface is correspondingly reduced.

The roller 3 is mounted on a shaft 30 hav-

ing at one end fast and loose pulleys 31 and 32 and is reciprocated on its shaft by means of a cam grooved pulley 33 engaging a coned roller 34 the spindle of which is carried in a bracket 35 secured to one of the main frame members 11 and having set screws 36 and 37 to adjust the position of the roller 34 to take up wear. Should undue wear take place on the grinding block 20 the roller 3 may be 10 adjusted in relation thereto. To achieve this, the roller shaft 30 is mounted in adjustable bearings 38 in the frame members 11. Hence should the wear on the grinding block due to inequality of material be experienced the 15 roller can be adjusted in relation to the block rather than the block to the roller.

At the front of the mill a collecting box 40 is provided the base of which is constituted by a scraper blade 41 closely engaging the 20 surface of the roller 3 under the influence of springs 42 connected at their upper ends to the ends of the scraper blade and at their lower ends to arms 43 extending inwardly from the frame members 11. The collecting box 40 is also supported on a rod 44 extending across 25 the mill between brackets 45 on the frame members 11, the said scraper blade having a slotted lug or lugs 46 on its under side which engage over the rod 44. The collecting box 30 is also provided with an outlet 47, which as shown comprises an arcuate portion over 30 which a similarly constructed door is movable.

For ordinary viscous bodies the setting of the throat 2 in relation to the roller 3 may 35 be coarse, but when dealing with enamel dissolved in spirit it is frequently necessary to make this adjustment within narrow limits. With viscous materials it is frequently found necessary to warm the contents of the hopper 40 1 and throat 2 and this may be achieved by making the wall of the hopper and throat hollow as shown at 48 in Figure 3 and circulating therein a heating medium. The same methods may be applied to the roller which 45 as shown at 49 in Figure 3 is hollow or in some cases both hopper and roller may be cooled as temperature largely affects the wet vehicle which holds the material in solution or suspension and the degree of viscosity or 50 otherwise determines the fineness of grinding and the value of the resultant product.

I claim:—

The grinding mill for paint and like materials including a reciprocating roller, a 55 hinged frame carrying a hopper, feed throat and adjustable grinding block, manually operated means for turning the hopper, feed throat and grinding block about its pivot from its operative to its inoperative position, 60 locking means for retaining said frame normally in operative position but to permit adjustments and micrometer screws for adjusting said frame.

In witness whereof I affix my signature.
HENRY DRYSDALE.
